AUTOMATIC TELEPHONE EXCHANGE SYSTEM

Filed March 9, 1929

UNITED STATES PATENT OFFICE

KARL FREDRIK WINCRANTZ AND KARL GEORG JOHNSON, OF STOCKHOLM, SWEDEN,
ASSIGNORS TO TELEFONAKTIEBOLAGET L. M. ERICSSON, OF STOCKHOLM, SWEDEN,
A COMPANY OF SWEDEN

AUTOMATIC TELEPHONE-EXCHANGE SYSTEM

Application filed March 9, 1929, Serial No. 345,763, and in Sweden March 6, 1928.

The present invention refers to such automatic telephone exchange systems in which the incoming traffic from a central station is attended to and supervised at a local exchange by operators who receive the calls and establish the desired connections through the local automatic exchange on the principles of a semi-automatic system. More particularly, the invention relates to a simplified semi-automatic system especially adapted for small automatic telephone plants, such as private branch exchanges. The object of the invention is to provide semi-automatic working without the necessity of arranging special switch-boards for this purpose at the automatic station. This is rendered possible according to the invention by one or more of the telephone apparatus connected to the exchange being arranged to mediate the traffic coming from the central station. These apparatus, which preferably are of the common desk set type, are only provided with the signalling devices and switching means required for the handling of the traffic, such as call and supervisory lamps, keys, manual switches, or the like, and an impulse transmitter, whereas the switching devices required for the connection of the telephone apparatus to the different junction lines are arranged at the automatic exchange. The latter devices may consist, for instance, of relays adapted to be actuated from the telephone apparatus by means of keys, switches or the like. The invention furthermore aims at facilitating an occasional distribution of the traffic onto two or more apparatus, the calls being normally received at a main apparatus, however, which is provided with switching devices for the purpose of transferring of one or more calls to an auxiliary apparatus, when the traffic is heavy, so that these calls may be handled at the last-mentioned apparatus. The invention will be described more closely.

ly with reference to the accompanying drawings, which illustrate two telephone apparatus A_1 and A_2 intended for the handling of the traffic received at a private branch exchange, together with appertaining signalling and switching means. The apparatus A_1 is the main apparatus to which all calls are normally directed, whereas the apparatus A_2 is an auxiliary apparatus capable of taking charge of a portion of the traffic when required. The parts pertaining to the apparatus A_1 are disposed underneath the chain dotted line H_1 in the drawing, whereas the parts pertaining to the auxiliary apparatus A_2 are disposed above the chain dotted line H_2 . The parts situated between these lines are switching devices pertaining to the apparatus A_1 and A_2 and to the main lines entering from the central station, and which are disposed at the automatic exchange proper. In the drawing, only one main line HL is shown, but a number of such lines may obviously be arranged in an analogous manner. A selector V connected to the main line HL and with appertaining switching means is shown to the right of the vertical chain dotted line H_3 .

The main apparatus A_1 and the auxiliary apparatus A_2 are of the desk set type. They are provided with a micro-telephone comprising a head phone T_1 and T_2 respectively, and a micro-phone M_1 and M_2 respectively, a finger dial D_1 and D_2 respectively, a hook switch HO_1 and HO_2 respectively, two signal lamps AL_1 and AL_2 , and KL_1 and KL_2 respectively, and a number of keys SK_1 , DK_1 , BK_1 and SK_2 , DK_2 , BK_2 respectively, which are individual to the main line HL . In addition, the main apparatus A_1 is provided with keys KBK , MBK and KK , which are common to all main lines. Disregarding the special means for handling the incoming traffic, the apparatus A_1 , A_2 are equivalent to the other apparatus connected to the automatic exchange. Thus, they may be disposed in any

suitable places within the ware house or the like to be served by the exchange. The nature of the other devices will be apparent from the description of the switching operation hereinbelow.

- 5 The central station may be a manual or an automatic station but is assumed in the following to be a manual station. On a call from the main station a call relay IR is actuated by means of alternating current over the line circuit 1 containing a winding 3 on the said relay connected between the two line branches L_1 , L_2 over a condenser 2. When the relay IR attracts its armature, a holding circuit 4 for another winding 5 on the call relay is closed. Furthermore, a current path 6 is closed through a call lamp AL_1 at the main apparatus AL_1 . When the operator sees the lamp AL_1 lighting up, she depresses the key SK_1 of the corresponding line HL_1 for a moment, a circuit 7 being thus closed, said circuit containing two relays AR_1 , BR_1 and a resistance R_1 . The relay AR_1 receives holding current over a circuit 8 containing a resistance R_2 and a contact 9 on the operator's hook switch HO_1 which latter contact is broken when the operator's microphone is hooked on. Moreover, the relay AR_1 closes a circuit 10 through 10 a slow-acting relay GR which then attracts its armature and connects the line HL_1 to the telephone apparatus A_1 over back contacts on a shifting relay DR_1 . The holding circuit 4 for the relay IR is then broken at the same time, thus causing the call lamp AL_1 to go out. Furthermore, the relay GR closes a current path 11 for a control lamp KL_1 . After the operator has been informed of the number desired, she depresses the self-locking key DK_1 , whereby the relay DR_1 is energized. The latter relay shifts the operator's speaking circuit from the outer line to the end of the line entering the automatic exchange, a circuit 12 being thus closed over 15 operating contacts on the previously actuated relay BR_1 and through a line relay LB . The latter circuit also contains the impulse transmitter D_1 of the operator. When DR_1 attracts its armature, the two line branches L_1 , L_2 are united over a contact 13, whereby the line circuit is kept closed. Moreover, a circuit 14 is formed, which contains a relay ER which now attracts its armature and, in turn, closes a branch circuit over the contact 15. 20 and through the resistance R_3 . In addition, the relay ER closes a branch circuit to the control lamp KL_1 at the contact 16 of the relay. The relay ER furthermore closes a circuit 17 through a relay PR switching itself into a holding circuit over its contact 18 while at the same time closing a circuit for the winding 20 of a relay OR at the contact 19. The latter relay then switches its second winding 21 into a holding circuit 22. At the same time the circuit 17 for the relay PR

is interrupted, which in turn interrupts the circuit for the operating winding 20 on the relay OR . Furthermore, the relay OR closes a branch circuit to the relay GR at the contact 23. Moreover, the relay OR closes the circuit for a slow-acting relay NR at the contact 24, which latter relay in turn connects an inductive resistance RD to the line branch L_2 .

When the line relay LB attracts its armature, an impulse circuit 25 is closed through the driving magnet DM of the selector V , said impulse circuit containing an impulse machine IM . Thus the selector will be driven step by step until it finds an unoccupied trunk line, when a test circuit 26 is closed through the one winding 27 of a stop relay SR which now attracts its armature and breaks the operating circuit 25 of the selector at the same time switching its other winding 28 into a holding circuit over the third contact arm K_e of the selector. At its contacts 29, 30 the relay SR furthermore connects the line HL to the trunk line in question over the contact arms K_a , K_b of the selector. When the line has thus obtained connection with the impulse receiver of the automatic exchange, the operator in known manner receives a buzzer signal, whereupon the impulse transmitter D_1 may be actuated to establish the connection over the automatic exchange.

As soon as the operator has completed the connection and satisfied herself of the fact that the called line is not engaged, the operator may disconnect herself from the connection by pulling up the key DK_1 , the relay DR_1 then releasing its armature and again connecting the operator's speaking set to the external line. When the operator finally hooks on her microtelephone, the current path 8 is interrupted, the relays AR_1 and BR_1 thus releasing their armatures and completing the connection. The supervising circuit of the main line is now kept closed by a relay HR connected between the line branches. Before the called subscriber answers, the connection is maintained over the automatic exchange through a branch of the circuit 12 over the resistance RD . The condensers 31, 32 inserted into the speaking circuit separate the direct current circuits from each other.

When the called subscriber answers, a circuit 33 is established over the line of the called subscriber and through a relay CR , which now attracts its armature and breaks the circuits 14, 15, the short circuit of the winding 34 of the relay FR being thus opened. The latter relay therefore attracts its armature and connects itself into a holding circuit 35 containing the second winding 36 of the relay. At the same time the circuit is interrupted for the relay ER , which in turn interrupts the circuit for the winding 34 of the relay FR . When the relay ER is de-

energized, the circuit is interrupted for the control lamp KL_1 , the operator thus finding that the subscriber has answered.

When, on the termination of the conversation, the called subscriber hangs up his microtelephone, the circuit 33 containing the relay CR is broken, which relay is now de-energized so as to interrupt the holding circuit for the relays OR and FR . When OR is deenergized, the circuit is interrupted for the relay GR , whereby the main line is disconnected. When OR is deenergized, also the relay NR releases its armature, whereby the holding circuit from RD over the line branch L_2 and through LB is broken, causing the automatic connection to be interrupted in known manner.

In case of the called subscriber failing to answer, which is evidenced by the control lamp KL remaining alight, the operator may again switch herself into the connection by depressing the key SK_1 , the relays AR_1 and BR_1 being then again rendered operative in the manner previously described. Thus the operator is again in connection with the external line and may communicate with the calling subscriber. The operator may then interrupt the connection by depressing the key BK_1 which closes a circuit 33 for the relay CR , which will have the same result as if the called subscriber answered. When the operator releases the key BK_1 anew, the latter circuit is interrupted and the relay CR is de-energized, all relays on the automatic side being then deenergized in the manner previously described. When the operator then hooks on her microtelephone, the circuit for the relays AR_1 and BR_1 is interrupted, whereby the connection with the central station is interrupted in the manner previously described.

If the called subscriber is occupied, which is indicated by a tone in the head-phone of the operator, the operator may break the connection by actuating the key BK_1 in the manner just described.

In order to facilitate the work of the operator in periods of heavy traffic, arrangements are provided to make it possible for the operator to disconnect her apparatus from the line, without it being necessary for this purpose to hook on her microtelephone. The said arrangements are such that the disconnection of the telephone apparatus takes place automatically when the operator, for the purpose of answering a call on another line, actuates the key SK_1 pertaining to said line, a branch being then established to the circuit 8 at the common point 38 over the circuit 7 and the appertaining answering key SK_1 of the line last calling. By reason of the large resistance R , contained in the circuit 8 the latter circuit now receives so small a current that its relays AR_1 and BR_1

release their armatures, the circuit 8 being thus interrupted.

On a call from the automatic telephone exchange to the central station a current path 39 is established, said path containing the line relay LB and a relay RR . The line relay starts the selector V in the manner previously described and establishes a test circuit through the winding 27 on the relay SR and over a fourth contact arm K_d on the selector. When the selector finds the calling circuit, the operating circuit 25 is broken in the manner previously described, by the relay SR being rendered operative. Hereby the line of the calling subscriber is switched on to the main line HL , the relay CR then receiving current in the manner previously described. When CR attracts its armature, the circuit for the relay PR is closed at the contact 40. PR attracts its armature and closes the circuit through the winding 20 of the relay OR , the latter relay in turn closing the contact 23 and thus actuating the relay GR which completes the connection to the main line. Normally, the outgoing traffic is thus effected altogether automatically without the aid of any operator.

By depressing the key KK the operator at the apparatus A_1 may at any time find out which main lines HL are occupied by conversations, the circuits for the appertaining control lamps KL_1 being then closed over the contact on the relays GR and HR .

When leaving her place the operator at the apparatus A_1 may transfer the handling of the traffic to the operator at the apparatus A_2 by depressing the self-locking key KBK . This results in that a relay KR is brought into operation, said relay preparing the switching-in of the call lamps AL_2 of the apparatus A_2 , while the control lamp KL_2 is shunted to the control lamp KL_1 . The call lamp AL_2 , then assumes the function of the lamp AL_1 in such manner that, when the relay IR attracts its armature by reason of a call, the lamp circuit is closed over a contact 41 on the relay KR . At the same time the relay TR is brought into operation, whereby the lamp AL_1 is disconnected. The operator at the apparatus A_2 may then carry out the same functions which have been described hereinbefore with reference to the apparatus A_1 , the operator at A_2 making use, however, of a set of relays AR_2 , BR_2 and DR_2 , which relays operate in a manner entirely analogous to that of the corresponding relays AR_1 , BR_1 and DR_1 . Thus the relays AR_2 and BR_2 serve to facilitate connection of the apparatus A_2 to the one or the other side of the connection, whereas the relay DR_2 controls shifting of the apparatus to the one or the other side. The key SK_2 as well as the keys BK_2 and DK_2 serve the

same purpose as the corresponding keys SK₁, BK₁ and DK₁ at the apparatus A₁.

If the operator requires occasional assistance from the other operator, she may switch over one or more incoming calls to the apparatus A₂. To this end the operator actuates the key MBK and simultaneously also one or more keys SK₁ for those main lines on which unanswered calls are to be found. Through the simultaneous actuation of the keys MBK and SK₁ the relays TR are actuated for the main lines in question, in that the circuit of the relay TR is then closed over a contact 42 on the relay MR. Hereby the circuit of the call lamps is switched over from the apparatus A₁ onto the apparatus A₂ in the manner previously described, whereupon the operator at the apparatus A₂ can attend to the desired connections. In this case, however, the control over the connections set up by the operator at A₂ remains with the operator at A₁, inasmuch as the control lamps KL₂ have not been switched in. Said switching over of calls may also be effected by a momentary actuation of the key KBK, all unanswered calls being then switched over, without any key SK₁ having to be actuated for this purpose. By arranging a plurality of keys KBK, corresponding to different groups of incoming main lines, the operator may switch over an arbitrary group of lines onto the assistant operator at will.

The apparatus A₁ and A₂ may also receive calls from other apparatus in the automatic exchange, and are for this purpose connected to the exchange similarly as other apparatus. If required, the operator at the main apparatus A₁ may assist in establishing connections over the central station, for instance in the case of long distance service connections, the operator then getting into communication with the station by depressing a key SK₁ on having first convinced herself, by depression of the control key KK, that the main line in question is unoccupied.

The apparatus A₁ and A₂ are thus to be regarded as ordinary subscriber's stations in the automatic exchange, and they are also intended to be used as such, for instance by the staff of an office or a warehouse. At the same time, however, they may also be served by the same staff in the manner above described, to mediate incoming as well as outgoing traffic.

We claim:

1. In a telephone system a main office, a branch office comprising an automatic exchange, main lines connecting the main office with the branch office and terminating in the automatic exchange, subscriber's telephone lines terminating in the automatic exchange, subscriber's stations having telephone apparatus associated with said subscriber's lines, one of said subscriber's apparatus being provided with means for mediating the incoming

traffic from the main office comprising switching means at the automatic exchange for connecting the telephone line of the mediating subscriber's apparatus with each of said main lines, circuits for said switching means, keys on the mediating apparatus for operating said switching means over said circuits, and call indicating means on the mediating apparatus for indicating calls from the main office.

2. In a telephone system a main office, a branch office comprising an automatic exchange, main lines connecting the main office with the branch office and terminating in the automatic exchange, subscriber's telephone lines terminating in the automatic exchange, subscriber's stations having telephone apparatus associated with said subscriber's lines, one of said subscriber's apparatus being provided with means for mediating the incoming traffic from the main office comprising switching means at the automatic exchange for connecting the telephone line of the mediating subscriber's apparatus with each of said main lines, circuits for said switching means, keys on the mediating apparatus for operating said switching means over said circuits, call indicating means on the mediating apparatus, and means for connecting a main line with a subscriber's line through the automatic exchange under the control of the mediating apparatus.

3. In a telephone system a main office, a branch office comprising an automatic exchange, main lines connecting the main office with the branch office and terminating in the automatic exchange, subscriber's telephone lines terminating in the automatic exchange, subscriber's stations having telephone apparatus associated with said subscriber's lines, two of said subscriber's apparatus, herein-after called main apparatus and auxiliary apparatus, being each provided with means for mediating the incoming traffic from the main office comprising switching means at the automatic exchange for connecting the telephone line of the mediating subscriber's apparatus with each of said main lines, circuits for said switching means, keys on the mediating apparatus for operating said switching means over said circuits, call indicating means on the mediating apparatus for indicating calls from the main office and circuits for said call indicating means, and means under the control of the main apparatus for shifting said circuits so as to transfer the calls from the main apparatus to the auxiliary apparatus.

4. A telephone system as claimed in claim 3, in which the means for transferring calls from the main apparatus to the auxiliary apparatus comprise keys individual to the main lines and controlling the call indicating circuits so as to allow of calls on any main line

to be transferred separately to the auxiliary apparatus.

5. A telephone system as claimed in claim 3, in which the means for transferring calls from the main apparatus to the auxiliary apparatus comprise a key on the main apparatus and a relay at the automatic exchange arranged under the control of said key and adapted to control the circuits of all the call 10 indicating means so as to transfer all the calls to the auxiliary apparatus on operating said key.

In testimony whereof we affix our signatures.
